[57] CLAIM

The ornamental design for a rake, as shown and de-
scribed.

DESCRIPTION

FIG. 1 is a broken prospective view of a rake showing
my new design therefore, it being understood that the
design is continuous throughout;FIG. 2 is a right side elevational view, it being under-
stood that the left side is a mirror image thereof;

FIG. 3 is a front elevational view;

FIG. 4 is a rear elevational view;

FIG. 5 is a top plan view; and,

FIG. 6 is a bottom plan view.

The handle of the claimed design is shown broken away
in FIGS. 1, 3 and 4 for ease of illustration.FIG. 4

FIG. 5

FIG. 6
